AUTOMATIC HOSE HOLDER

Filed Nov. 6, 1924

UNITED STATES PATENT OFFICE.

ROBERT J. MITCHELL, OF RICHMOND, MISSOURI.

AUTOMATIC HOSE HOLDER.

Application filed November 6, 1924. Serial No. 748,158.

To all whom it may concern:

Be it known that I, ROBERT J. MITCHELL, a citizen of the United States, residing at Richmond, in the county of Ray and State 5 of Missouri, have invented certain new and useful Improvements in Automatic Hose Holders, of which the following is a specification.

This invention relates to a device for supporting the nozzle of a garden hose and automatically moving the same in an arc, back and forth, so as to direct the stream of water issuing from the nozzle, uniformly over a relatively wide area, the object of 10 15 the invention being to obviate the necessity of holding the nozzle and manually directing the stream of water.

Another object of the invention is to provide a device for the purpose stated which 20 25 may be set up in position for use at any place desired and which will be entirely automatic in its action so that no attention on the part of the user will be required, means being provided whereby the force 30 35 of the stream of water issuing from the nozzle will be utilized to effect automatic operation of the device to move the nozzle back and forth.

Another object of the invention is to so 35 40 construct the nozzle holding means of the device that it will be adapted to support the hose nozzle at different angles so that the stream of water may be directed as desired.

Another object of the invention is to so 45 50 construct the nozzle holding means that the nozzle may be readily assembled therewith in various positions of angular adjustment and readily disconnected therefrom, as occasion may require and without the employment of tools of any character whatsoever.

The device embodying the invention is so 55 60 constructed and operates in such a manner as to support the hose nozzle and cause back and forth movement thereof in an arc, and the invention has, as a further object, to provide means whereby the extent of angular movement of the nozzle may be varied so that the stream of water issuing from the nozzle may be directed over a relatively narrow or a relatively wide area, as may be desired.

In the accompanying drawings:

Figure 1 is a view in side elevation of 55 60 65 the device embodying the invention in use.

Figure 2 is a front elevation of the device.

Figure 3 is a plan view of the device illustrating in full, dot and dash, and dotted lines, the various positions assumed by the parts of the device in its operation. 60

Figure 4 is detail vertical transverse sectional view through the hose nozzle clamping means of the device, taken substantially on the line 4-4 of Figure 1, looking in the direction indicated by the arrows. 65

The device includes a standard which is indicated in general by the numeral 1 and which comprises two sections, one indicated by the numeral 2 and the other by the numeral 3. The section 2 is of tubular form 70 and is provided at its lower end with a blade 4, and above the blade with a cross piece 5, against which pressure may be exerted by the feet of the user to force the blade 4 into the ground, as clearly shown 75 in Figure 1, and thereby establish the standard in upright position, as well as the component parts of the structure supported thereby, as will presently be explained. The section 3 of the standard comprises a 80 head 6 which is of yoke formation and is provided with a shank 7 in which is anchored the upper end of a rod 8 rotatably fitted into the upper end of the tubular section 2 of the standard, the head 6 being, 85 in this manner, mounted for swinging or oscillatory movement a suitable distance above the ground surface, when the device is set up for use.

The head or yoke 6 upstands vertically 90 from the shank 7 and constitutes side members which are indicated by the numeral 9, and journaled for rotation in these side members is a shaft 10 upon which is fixed a gear 11. The said gear 11 meshes with a 95 pinion 12 fixed upon a shaft 13 likewise mounted between the side members 9 of the yoke, and fixed upon said shaft 13 is a disc 14 constituting a rotor and supporting at its periphery a number of blades 15. The side members 9 of the yoke are provided with rearward extensions which are indicated by the numeral 16, and these, in turn, are provided with upward extensions indicated, one 100 by the numeral 17 and the other by the numeral 18. The head 6 and its side member extensions 17 and 18 are of sheet metal of a suitable strength and the extensions, therefore, possess a greater or less degree of resiliency, and the extension 17 is flat-sided 110 whereas the extension 18 is formed with a plurality of bends providing open-sided noz-

zle embracing portions indicated by the numerals 19, 20 and 21, the open sides of these portions being presented toward the adjacent side face of the extension 17, and the 5 hose nozzle, indicated in general by the reference letter N, being adapted to be disposed between the said extensions and in position to be embraced by any one or another of the said portions 19, 20 and 21. By reference 10 to the drawings, it will be observed that the extensions 17 and 18 of the side members of the yoke 6, and the disc or rotor 14, occupy substantially the same vertical plane, and that the nozzle embracing portion 19 of the 15 nozzle holding device is inclined upwardly and forwardly so that a hose nozzle disposed therein will be presented to direct a stream of water against the blades 15, in an upward direction, thus effecting rapid rotation of the 20 rotor and imparting rotary motion to the shaft 13 and, by way of the pinion 12 and gear 11, to the shaft 10, for a purpose to be presently described. The nozzle engaging portion 20 of the nozzle holding device, is 25 inclined downwardly and forwardly, as will be observed by reference to Figure 1, so that when the nozzle is arranged therein, the stream of water will be discharged in a more or less downward direction but, at the same 30 time, will be directed against the blades 15 and effect rotation of the rotor, as before stated. The nozzle embracing portion 21 is arranged horizontally and somewhat above the blades of the rotor so that when the nozzle 35 is arranged therein, the stream of water will be directed approximately horizontally and will reach the ground without striking the blades 15. Normally, due to the inherent resiliency of the side members of the yoke 40 and the extensions 17 and 18 thereof, the extensions are spread apart a sufficient distance to permit of the ready engagement of the hose nozzle in any one of the embracing portions 19, 20 and 21. In order that said 45 extensions may be closed so as to clamp the nozzle and hold the same in the desired position, a bracket member 22 is fixed upon the outer side of the extension 17 and is of general rectangular form and embraces the 50 two extensions with its unconnected side spaced a suitable distance from the outer face of the extension 18. Mounted upon this side of the bracket, for rocking movement, is a clamp which may be formed of wire or 55 rod material and is bent to provide side members 23, a bearing cross bar 24, a handle 25, and eyes 26 which pivotally engage the said side of the bracket 22. The bar 24 is designed to ride against the outer face of 60 the extension 18 when the handle 25 is swung upwardly or downwardly, and it will be observed the disposition of the bar and handle is such that when the handle is swung upwardly, the bar will ride away from the extension 18 and permit of the ready introduc- 65

tion or removal of the hose nozzle, whereas, on the other hand, when the said handle is swung downwardly, the bar 24 will ride against the outer face of the extension 18 and cause the said extension to exert clamping action against the hose nozzle disposed within any one of its embracing portions 19, 20 and 21. In this manner, a simple means is provided for arrangement and support of the hose nozzle in any desired position of angular adjustment. 70

The invention contemplates means which will now be described, for converting the rotary motion of the shaft 10 into an oscillatory or horizontal swinging motion of 80 the head 6 and the hose supporting or holding means associated therewith, so that the stream of water delivered from the nozzle of the hose may be directed over a relatively large area of the surface to be sprinkled. 85 For this purpose there is provided an arm 27 which is preferably of angle iron and is clamped, as at 28, to the upper end of the standard section 2 so as to be rigid with respect thereto. The upper and lower 90 flanges of the angle iron arm are formed with sets of vertically aligned openings which are preferably three in number, two of the sets being indicated by the numeral 29 and the third set by the numeral 30. The 95 openings in each flange are arranged in a series extending longitudinally of the respective flange near the outer end of the arm, and corresponding openings are designed to accommodate stems 31 which are 100 provided at the lower end of a vertically disposed guide member which is indicated in general by the numeral 32. Said guide member is preferably formed from a length of rod material bent to provide spaced parallel vertically extending side members 33 connected at their upper ends by a bend 34 and having their lower end portions twisted together as at 35 and then formed to provide the said stems 31. The openings 105 29 and 30 are all equidistantly spaced so that in one instance the stems 31 may be engaged through the openings 29, as illustrated in Figures 1 and 3 of the drawings, 110 and, in another instance, and under other conditions, may be engaged one in one set of the openings 29 and the other in the openings 30. In this manner, provision is made for supporting the guide 32 in upright position upon the arm 27 at different 115 distances from the standard 1 of the device. The numeral 36 indicates a crank arm which is located at one end of the shaft 10 and which consists of a portion 37 radial to the shaft and a portion 38 outstanding from the end of the portion 37 and working between the side members 33 of the 120 guide 32. A similar arm, indicated in general by the numeral 39 is provided at the other end of the shaft 10 and comprises a 125 130

portion 40 radial to the said shaft and a portion 41 outstanding from the end of the portion 40 and likewise adapted to work between the side members 33 of the said guide 32. By reference to the drawings, and particularly to Figure 1 and 3 thereof, it will be observed that the portion 37 of the arm 36 is of greater length than the portion 40 of the arm 39, and the purpose 10 of so proportioning these parts will be presently explained.

From the foregoing description, it will be evident that the section 2 of the standard 1, and also the arm 27 carried thereby as 15 well as the slide 32 are all stationary. Assuming now that the member 38 of the crank arm 36 is working in the slide 32 and that the hose nozzle has been disposed within either of the hose nozzle embracing portions 19 or 20 of the hose holding means, and that water is issuing from the nozzle, the stream will strike the blades 15 of the rotor 14, resulting in rapid rotation of the shaft 10. As the shaft rotates, the portion 25 38 of the crank arm 36 will work between the side members 33 of the slide 32 and as the slide is stationary, and the head 6 supporting the hose holding means is rotatable with relation thereto about a vertical axis, 30 the said head and its associated parts will be oscillated about its vertical axis, thereby directing the stream of water back and forth over a relatively wide area of the surface to be sprinkled. It will also be understood that as the stream of water issuing 35 from the nozzle strikes the blades 15, the stream will be broken up somewhat, so that the water will be more equally and more widely distributed. Also, it will be evident 40 that the stream may be delivered as a fine stream or in more or less of a spray, by adjusting the nozzle in the usual manner to effect a change in the character of the stream, but that due to the proximity of 45 the discharge end of the nozzle to the blades of the rotor, the rotor will, under all conditions, be rotated. It will be evident that by arranging the hose nozzle in the embracing portion 19, the nozzle will be presented 50 in a more or less upwardly inclined direction and when disposed within the embracing portion 20, will be presented more or less downwardly, so that by changing the nozzle from one to the other of the embracing 55 portions, an area relatively remote from the device may first be sprinkled, for example, and then an area nearer to the device may be sprinkled or sprayed. It will also be evident that the device is useful 60 where it is not desired to broadly distribute the stream but to direct the same upon a more or less restricted area, by adapting the hose nozzle in the embracing portion 21. If it should be desired to somewhat restrict 65 the width of the area over which water is

to be delivered, this may be effected by lifting the slide 32 to disengage its bends 31 from the openings 29 in which they were engaged under the previously described operation and then rotating the head 6 70 about its axis through substantially ninety degrees and placing the slide 32 with its stems 31 engaging one in the openings 30 and the other in the next adjacent set of the openings 29, and engaging the portion 75 41 of the crank arm 39 in the said slide. The portion 40 of the said crank arm 39 being of a length less than that of the portion 37 of the crank arm 36, the angular movement of the head 6 will be of less degree than in the preceding adjustment of the parts.

Having thus described the invention, what I claim is:

1. In a device of the class described, a 85 relatively stationary member, a member supported thereon for oscillatory movement, means upon the oscillatory member for supporting a hose nozzle, a fluid-impact rotor upon the oscillatory member adapted to be 90 operated through the medium of a stream of water delivered from a hose nozzle carried by said nozzle supporting means, a shaft rotatably carried by said oscillatory member and having a crank portion at one 95 end, means operatively connecting said shaft and rotor to cause said shaft to be rotated by said rotor, and a stationary guide element carried by said stationary member and engaging said crank portion to cause oscillation of said oscillatory member during rotation of said shaft.

2. In a device of the class described, a 105 relatively stationary member, a member supported thereon for oscillatory movement, a shaft mounted upon the oscillatory member, a fluid-impact rotor upon the said oscillatory member, means for transmitting rotary movement from said rotor to said shaft, means upon said oscillatory member for supporting a hose nozzle in position to direct a stream of water against said rotor and impart rotary movement to the rotor, a 110 guide upon the stationary member, and a crank upon the said shaft coacting with the said guide to effect oscillation of the oscillatory member through rotation of the shaft.

3. In a device of the class described, a 115 relatively stationary member, a member supported thereby for oscillatory movement, a 120 fluid-impact rotor upon the oscillatory member, means upon the oscillatory member for supporting a hose nozzle in position to direct a stream of water against the rotor and cause the rotor to be operated through the medium of a stream of water delivered from the nozzle, a shaft upon the oscillatory member driven from the rotor, crank arms of different lengths upon the shaft, and a 125 fixed guide upon the stationary member for 130

the selective cooperation of the crank arms therewith, whereby to impart oscillatory motion to the oscillatory member through rotation of the shaft through arcs of different lengths.

4. In a device of the class described, a relatively stationary member, a member supported thereon for oscillatory movement, a fluid-impact rotor upon the oscillatory member, means upon the oscillatory member for supporting a hose nozzle in position to direct a stream of water against the rotor and cause the rotor to be operated through the medium of a stream of water delivered from the nozzle, a rotary shaft upon the oscillatory member, crank arms of different lengths upon the shaft, an arm extending from the relatively fixed member, and a guide adjustably supported upon the said arm whereby to occupy positions at different distances from the oscillatory member, the said crank arm being interchangeably engageable with the slide whereby to effect oscillation of the oscillatory member through arcs of different lengths.

5. In a device of the class described, a relatively stationary member, a member supported thereon for oscillatory movement, means upon the oscillatory member for supporting a hose nozzle at various positions of inclination, a fluid-impact rotor upon the oscillatory member disposed for operative

engagement by a stream of water delivered from a hose nozzle carried by the nozzle supporting means, a crank shaft rotatably carried by said oscillatory member and rotated from said rotor, and a guide rigid with said stationary member and engaging a crank portion of said crank shaft for effecting oscillation of said oscillatory member as the crank shaft rotates.

6. In a device of the class described, a relatively stationary member having means whereby it may be anchored in the ground, a member rotatably supported thereon for oscillatory movement and including a head having spaced members provided with upwardly extending arms, the said arms constituting clamping members for engaging a hose nozzle, and one having nozzle-receiving pockets disposed one above another and at varying angles, means for holding the arms in clamping engagement with a nozzle disposed therebetween and within one of the pockets a rotor mounted between the spaced members of the head and having blades disposed for engagement by a stream of water issuing from a nozzle secured between said arms and coacting means upon the said fixed and oscillatory members operated through the rotor for effecting oscillation of said oscillatory member.

In testimony whereof I affix my signature.
ROBERT J. MITCHELL. [L. S.]
